UNITED STATES PATENT OFFICE.

GEORGE WASHBURN WIDNER, OF BRADFORD, KANSAS.

RAIL-TIE.

1,160,227.

Specification of Letters Patent.

Patented Nov. 16, 1915.

Application filed June 24, 1915. Serial No. 36,074.

To all whom it may concern:

Be it known that I, GEORGE WASHBURN WIDNER, citizen of the United States, residing at Bradford, in the county of Wa- 5 baunsee and State of Kansas, have invented certain new and useful Improvements in Rail-Ties, of which the following is a specification.

This invention relates to rail ties for use 10 upon railroad tracks, and it has for its object the provision of an improved device of this character constructed in such manner that it may be economically manufactured from strap metal, may be expeditiously 15 placed in position and when placed in position will provide for the necessary expansion and contraction of the track while at the same time limiting movement of the rails away from each other, whereby the destructive 20 and fatal accidents which so frequently occur by reason of the rails "spreading" will be effectively prevented.

Further objects and advantages of the invention will be set forth in the detailed description which now follows:

In the accompanying drawing Figure 1 is a transverse sectional view of a railroad track with the rail tie in longitudinal section and Fig. 2 is a perspective view of the rail 30 tie with the parts in disassembled position.

Like numerals designate corresponding parts in both figures of the drawing.

Referring to the drawing, 5 designates the usual cross tie and 6 the rails of a railroad track. The rail tie is made up of a pair of complementary sections 7 and 8. These sections have at their outer ends hook like flanges 9 and 10 arranged to engage over the outer edges of the base flanges 11 of rails 6. The section 7 of the tie is bent upwardly at 12, then bent to form a horizontal portion 13, and then bent to form a down turned hook like terminal portion 14. The section 8 on the other hand is bent at its inner end 40 to form an upturned hook like portion 15 arranged to have inter-engagement with the hook like portion 14 of section 7. After these sections have been inter-engaged as shown in Fig. 1 clamping plates 16 and 17 having extensions 18, arranged to engage over the inner edges of the base flanges 11 of rails 6, are secured in position by bolts 19. These bolts pass through the sections 7 and 8 and through slots 20 of the clamping plates 16 and 17 whereby adjustment for these plates is provided. A bolt 21 passes

through the hook like terminal end 15 of section 8 and through slots 22, formed in the horizontal portion 13 with the hook like portion 14 of section 7. It will therefore be seen that with the parts in the position illustrated in Fig. 1, movement of the rails away from each other is positively prevented while a limited movement of said rails toward each other is possible by reason of the provision of slots 22, whereby slight expansion and contraction of the parts is provided for, but at the same time spreading of the rails is prevented.

While the elements shown and described are well adapted to serve the purposes set forth, it is to be understood that the invention is not limited to the precise construction shown, but that it includes within its purview such changes as come with the spirit of the appended claims.

Having described my invention, what I claim is:

1. A rail tie made up of a pair of complementary sections, means for securing the outer ends of said sections to the base flanges of the rails of a railroad track, said sections having slideable inter-engagement with each other at their inner ends, and means for securing said slideably engaged sections to each other in such manner as to prevent movement of the sections away from each other, but permitting limited movement of the sections toward each other.

2. A rail tie of the character described made of strap iron and formed in a pair of complementary sections, one of said sections being provided with a down-turned terminal hook portion at its inner end and the other of said sections being provided with an up-turned terminal hook portion at its inner end which has sliding engagement with said down-turned terminal hook portion, means for securing the outer ends of said sections rigidly to the base flanges of the rails of a railroad track, and a fastening device traversing the inter-engaged hook portions of the members and arranged to prevent movement of the sections away from each other while permitting a limited movement of said sections toward each other.

3. A rail tie made up of strap iron and formed in a pair of complementary sections, one of said sections being provided with a down-turned terminal hook portion at its inner end, and the other of said sections being provided with an up-turned terminal

hook portion at its inner end, said hook portions having slideable engagement with each other, a member traversing said hook portions and constructed and arranged to limit 5 the movement of said hook portions away from each other, but permitting a limited movement of said sections toward each other, and means for securing the outer ends of said sections in rigid relation to the base 10 flanges of said rails.

4. A rail tie made up of strap iron comprising a pair of complementary sections, said sections being provided with inter-engaging hook members at their inner ends, 15 means for securing the outer ends of said

sections rigidly to the base flanges of the rails of a railroad track, and a fastening device traversing said hook portions, the opening in one of said hook portions through which said fastening device passes being 20 larger than said fastening device to permit a limited sliding movement of one of the sections with relation to the other.

In testimony whereof I affix my signature in presence of two witnesses.

GEORGE WASHBURN WIDNER.
